UNITED STATES PATENT OFFICE.

CHARLES F. WAGNER, OF PITTSBURGH, PENNSYLVANIA, ASSIGNOR TO WESTINGHOUSE ELECTRIC & MANUFACTURING COMPANY, A CORPORATION OF PENNSYLVANIA.

CURRENT-COLLECTING DEVICE.

Application filed July 5, 1922. Serial No. 572,915.

To all whom it may concern:

Be it known that I, CHARLES F. WAGNER, a citizen of the United States, and a resident of Pittsburgh, in the county of Allegheny and State of Pennsylvania, have invented a new and useful Improvement in Current-Collecting Devices, of which the following is a specification.

My invention relates to current-collecting devices and it has particular relation to means for equalizing the current traversing the several brushes of a dynamo-electric machine.

Heretofore, it has been observed that the current-collecting brushes for dynamo-electric machines, and particularly machines of the rotary converter type which employ a large number of brushes connected in parallel relation and which co-operate with a single collector ring, are subjected to unequal wear. Extensive experiments have, therefore, been conducted for the purpose of determining the cause of the inequality in brush wear.

As a result of investigation it has been ascertained that one of the principal causes of unequal brush wear is the unequal flow of current through the several brush members which causes the decomposition of the brushes subjected to excess current flow. The inequality of current flow in the different brushes may, in turn, be attributed to several causes, such as the formation of a film of air of substantially wedge shape between the brush member and the collector ring; carbon deposits on the contact surfaces of certain of the brushes; unequal pressures exerted by the brush springs; uneven contact surfaces of the brush members; inequality in the chemical constituents of the contact surfaces and particularly those of the brush members; the unstable volt-ampere characteristics of the brushes in general and the effect of non-uniform external conditions, such as the resistance and the reactance of the paths of the current from the brushes, as in the brush-holder stand to which the brush shunts are electrically connected.

One of the objects of my invention is to provide means for overcoming the difference in impedance existing in the current paths of a plurality of brushes connected in parallel relation and to stabilize or balance the flow of current therethrough by

inserting a resistor element in series with the individual brushes.

Another object of my invention is to provide a resistor element, of the character described, that may be quickly and easily connected in the brush circuits of a dynamo-electric machine without changing the structure thereof, and that is so constructed and arranged as to occupy but a small space.

In the accompanying drawing:

Figure 1 is a side elevational view of a brush holder provided with a resistor element constructed and arranged in accordance with my invention.

Fig. 2 is a detail perspective view of the resistor element illustrated in Fig. 1.

Fig. 3 is a view of another form of my invention.

Fig. 4 is a diagrammatic view illustrating the difference between the volt-ampere characteristics of a brush operating respectively with and without a resistor element.

Referring to the drawing, a brush holder of standard construction is shown as comprising a brush box 1 which is adapted to receive and retain a brush member 2 for co-operation with a collector ring 3. The brush box 1 is provided with a vertically extending portion 4 which is secured to a bracket element 5 by means of a bolt 6.

The member 4 is provided with a serrated surface 7 for co-operation with a similar surface formed on the bracket element 5, and it functions to maintain the brush holder securely in its adjusted position. The element 4 is insulated from the bracket element 5 by means of a strip of insulating material 8 which is clamped between the coacting serrated surface 7 and also by means of an insulating spacing washer 9 disposed between the bolt 6 and the outer surface of the member 4. The bracket element 5 is mounted upon a stud 10 carried by the frame of the dynamo-electric machine, not shown.

The upper portion of the bracket 5 is provided with a vertically extending lug 11 to which a resistor element, indicated, as a whole, at 12, is secured at one end by means of screws 13. The resistor element 12 is preferably of sinuous configuration, as is best illustrated in Fig. 2, whereby a relatively long current path is obtained therethrough without materially increasing the overall dimensions of the resistor ele-

ment. The outer end of the element 12 is provided with a downwardly extending rod or bar 14 to the lower extremity of which a shunt attachment 15 of the brush member 5 2 is secured, as indicated at 16.

In Fig. 3 is illustrated another form of my invention in which the resistor element 12 is bent upon itself into substantially inverted U-shape, the legs of which are formed 10 with supporting feet 17 and 18. The foot 17 of the resistor element is electrically connected to the upper surface of the bracket member 5, as at 19. The foot 18 is also secured to the bracket 5 at 20 but 15 is insulated therefrom by means of spacing washers 21 of insulating material. The foot portion 17 overhangs the edge of the bracket 5 and is provided with an eye portion 22 to which the shunt attachment 15 of the 20 brush member is secured by means of a bolt 23.

The effect of the above described construction may be best explained with reference to Fig. 4 of the drawings, which 25 diagrammatically illustrate the volt-ampere characteristics of a brush operating with and without a resistor element. From an inspection of the figure referred to, it will be observed that the voltage drop across a 30 metallized carbon brush increases but slightly with a large increase in current, as indicated at 24. This voltage drop across a single brush is insufficient to function as a regulating voltage to maintain the currents 35 through the several associated brushes substantially equal.

A resistor element 12 is, therefore, connected in series with each of the individual brushes, and the respective brush and resistor elements are in turn, connected in 40 parallel relation. A greater regulating voltage is, therefore, obtained by reason of the fact that, if more current tends to flow through one of the brushes and its resistor 45 than through another similar group of elements, the potential difference established across the first resistor, being proportional to the current of greater value, will be sufficient, as illustrated by the curve 25, to 50 function as a regulating voltage, to effect an increased flow of current through the brush and resistor being traversed by the lesser current.

The regulating action of this potential 55 difference established across the brush and the resistor carrying the larger current is effected by reason of the fact that a greater potential difference is available to cause more current to traverse the other brush 60 and resistor than would be caused by the

relatively small potential difference across the brush alone.

By means of the constructions above set forth, an accurate regulation of current flow through the brushes is obtained and the 65 destructive action of excess currents traversing the brushes is materially diminished.

I claim as my invention:

1. A current-collecting device comprising a brush holder adapted to support a brush 70 for co-operation with a rotating contact member, and a resistor element carried by said brush holder and connected in series with said brush.

2. A current-collecting device comprising 75 a brush holder adapted to support a brush for co-operation with a rotating contact member, and a sinuous resistor element carried by said brush holder and connected in series with said brush.

3. A current-collecting device comprising 80 a brush holder adapted to support a brush for co-operation with a rotating contact member, and a resistor element carried by 85 said brush holder and connected in series with said brush, said resistor element being so formed that the current path therethrough is of greater length than the overall length of said element.

4. A current-collecting device comprising 90 a brush holder adapted to support a brush for co-operation with a rotating contact member, and a resistor element carried by 95 said brush holder and connected in series with said brush, said resistor element being of non-laminated construction and bent upon itself to provide a current path of greater length than the overall length of said element.

5. A current-collecting device comprising 100 a brush holder adapted to support a brush for co-operation with a rotating contact member and a resistor element of non-laminated construction and sinuous configuration 105 having one end thereof secured to said brush holder and the other end electrically connected to said brush member.

6. A current-collecting device comprising 110 a brush holder adapted to support a brush for co-operation with a rotating contact member, and a resistor element consisting of a relatively flat strap bent upon itself and secured at one end to said brush holder and at the other end electrically connected to 115 said brush.

In testimony whereof, I have hereunto 115 subscribed my name this 28th day of June 1922.

CHARLES F. WAGNER.
